182,431

CHRISTMAS WREATH OR SIMILAR ARTICLE

Erich H. Moessen, Kalamazoo, Mich.

Application March 14, 1957, Serial No. 45,252

Term of patent 14 years

(Cl. D29—1)

Fig. 1 is a front elevational view of a Christmas wreath or similar article; and

Fig. 2 is a reduced front perspective view thereof.

I claim:

The ornamental design for a Christmas wreath or similar article, as shown.

References Cited in the file of this patent

UNITED STATES PATENTS

1,703,072	Becker	Feb. 19, 1929
1,980,708	Szel	Nov. 13, 1934